(57) **CLAIM**

The ornamental design for a smoking pipe, as shown and described.

DESCRIPTION

FIG. 1 is a rear perspective view of the smoking pipe in accordance with the present design, in an open position; FIG. 2 is a front perspective view of the smoking pipe shown in FIG. 1; FIG. 3 is a top plan view of the smoking pipe shown in FIG. 1;

FIG. 4 is a bottom plan view of the smoking pipe shown in FIG. 1;

FIG. 5 is a side elevation view of the smoking pipe shown in FIG. 1;

FIG. 6 is a rear end view of the smoking pipe shown in FIG. 1;

FIG. 7 is a rear perspective view of the smoking pipe in accordance with the present design, in a closed position; FIG. 8 is a front perspective view of the smoking pipe shown in FIG. 7;

FIG. 9 is a top plan view of the smoking pipe shown in FIG. 7;

FIG. 10 is a bottom plan view of the smoking pipe shown in FIG. 7;

FIG. 11 is a side elevation view of the smoking pipe shown in FIG. 7; and,

FIG. 12 is a rear end view of the smoking pipe shown in FIG. 7.

The broken lines shown in the drawings depict portions of the smoking pipe that form no part of the claimed design.

1 Claim, 4 Drawing Sheets
